Application May 8, 1934, Serial No. 724,546

33 Claims. (Cl. 12—33)

This invention relates to improvements in machines for applying pressure to shoe bottoms and is illustrated herein as embodied in a machine for use in cement-attaching soles to shoes.

5 An object of the invention is to provide an improved pad box for use in applying pressure to shoe bottoms which may be used with equal facility for operating on various styles and sizes of shoes, particularly youths' and children's shoes.

10 In accordance with the foregoing, a feature of the invention comprises an improved pad box structure containing a sole-receiving pad and provided with a mask plate arranged for movement longitudinally of the pad to adapt it for operating upon soles of different lengths. As illustrated herein and in accordance with another feature of the invention the mask plate carries a plurality of sole-engaging fingers or feelers which are pivoted on the mask plate and are provided with 15 shoe gages for positioning a shoe relatively to a sole placed by an operator on the pad. The sole-engaging feelers are arranged to be moved yielding against the edge face of the sole and to be locked in position after they have found the sole, thereby locating the shoe gages properly to position a shoe relatively to the sole. Since the mask plate is movable longitudinally of the pad the feelers can, of course, be adjusted properly to 20 accommodate different sizes of shoes.

25 In accordance with still another feature of the invention the sole-engaging fingers or feelers and the locking means are actuated by mechanism mounted on the pad box independently of the mask plate and arranged to actuate the feelers in any position into which they may be 30 adjusted longitudinally of the pad box. As illustrated, the actuating mechanism comprises an elongated bar supported by toggles and arranged to engage a roll on an arm connecting 35 the actuating mechanism with the feelers. The length of the bar is such that the roll will always be engaged to operate the feelers and the locking mechanism irrespective of the position into which the mask plate and feelers are moved 40 longitudinally of the pad.

45 Another feature of the invention resides in novel means for pivoting the forward portion or section of the pad box relatively to its central and rear portions about a virtual axis located 50 in a predetermined position substantially at the forward end of the central portion of the pad box and in a plane coinciding substantially with the sole-engaging surface of the pad. The pivoting means, as illustrated herein, comprises a 55 fixed support, a movable support, and mechanism

for moving the movable support in a predetermined path while permitting the forward or movable section of the pad box to remain in contact with the fixed support.

The above and other objects and features of 5 the invention will now be described with reference to the accompanying drawings and pointed out in the appended claims.

In the drawings,

Fig. 1 is a front elevation of a pad box embodying our invention including also gage mechanism for positioning the heel portions of the shoe and sole on the pad and parts of the pressure-applying mechanism of a cement sole-attaching machine;

Fig. 2 is a sectional view taken through the longitudinal center line of the pad box shown in Fig. 1;

Fig. 3 is a plan view of the forward end of the pad box with parts broken away and in section;

Fig. 4 is a detailed view in front elevation of the mechanism for operating the forepart positioning gages of the pad box; and

Fig. 5 illustrates a portion of the operating connections for the sole and shoe-positioning 25 gages.

The invention is illustrated herein as embodied in a cement sole-attaching machine of the type disclosed in an application for Letters Patent of the United States Ser. No. 636,202, filed October 30 30 4, 1932, in the name of Milton H. Ballard et al. Accordingly, the main casting 10 of the pad box is shown in Fig. 1 as secured by screws 12 to a forwardly projecting portion of a shelf or bracket 14 which projects radially of the rotary turret of the machine. On this stationary casting 10 are movably mounted a forward casting 16 for supporting the forepart of a fluid-filled pad P carried by the pad box and adapted to receive a sole and shoe, and a second casting 18 slidably mounted on vertical guideways 19 formed on the right-hand portion of the casting 10, as viewed in Fig. 1, the second casting 18 being arranged to support the rear or heel-engaging portion of the pad P. The casting 18 is held in 40 position on the guideways 19 by a pair of substantially horizontal links 20, located at opposite sides of the pad box and pivoted at their forward ends to pins 21 mounted in the casting 10 and pivoted at their opposite ends to pins 23 45 carried by the casting 18. A pair of bell crank levers 22, pivoted at opposite sides of the main casting 10 below the links 20 on a transverse shaft 24 mounted in the side walls of the casting 10, are provided with lower arms which are in- 50 55

terconnected by a cross portion 25 (Fig. 2) extending transversely of the casting 18, the portion 25 surrounding a horizontal shaft 26 the opposite ends of which are supported in downwardly projecting ears formed at opposite sides of the casting 18. The interconnected bell crank levers 22 have upwardly extending arms 28 which are connected by heavy springs 30 to a fixed shaft 32 supported in the opposite side walls of the stationary casting 10 and extending through the casting transversely of the pad P, the central or intermediate portion of the shaft 32 being supported by a wall 33 extending upwardly from the base of the casting 10. The springs 30 act to hold the movable casting 18 in its uppermost position on the guideways 19, this position being determined by a cam 34 (Fig. 2) carried by a transverse shaft 36 mounted in the casting 18, the cam 34 being arranged to engage a stationary ledge or shelf 38 projecting horizontally from the upper portion of an upstanding wall 37 which forms one end of the main casting. The shaft 36 is provided with a hand wheel 40 (Fig. 1) by which the cam 34 25 may be rotated into different positions to vary the heightwise position of the casting 18 on the vertical guideways 19 relatively to the main casting 10, the horizontal links 20 and the bell crank levers 22 forming in effect a parallel motion arrangement whereby the casting 18 is 30 moved in a substantially vertical direction.

The movable casting 18 is provided with mechanism for positioning the heel ends of a sole and shoe on the pad, such mechanism being indicated generally in Figs. 1 and 2 by the reference numeral 42 and comprising a pair of sole-engaging fingers and a separate pair of shoe-engaging fingers, each pair being mounted for equal and opposite pivotal movement independently of the other pair laterally of the pad. This heel-end positioning mechanism is not claimed herein since it is not of our invention. It is, however, fully disclosed and claimed in Letters Patent of the United States No. 2,005,754, granted June 25, 1935, on an application filed in the name of Robert Sandberg. The casting 18 is also provided with means for varying the heightwise position of the heel portion of the pad P in accordance with the height of heel which is to be attached to the shoe, such means including a pair of plates, indicated by the reference numeral 43 in Fig. 2, which are movable longitudinally of the casting 18 and are arranged to enter a recess in the heel end of the pad when the casting 18 is adjusted heightwise relatively to the main casting by means of the cam 34. Since this mechanism likewise forms no part of our invention it is not claimed herein but is fully disclosed and claimed in an application for Letters Patent of the United States, Serial No. 722,537, filed April 26, 1934, in the name of Frank Kennison.

The casting 16, which supports the forepart of the pad P, is connected to the main casting 10 in such a manner that, in order to adjust the forepart of the pad into a proper angle for the spring of the last in the shoe being operated upon, the casting 16 is moved about a virtual axis located substantially in the plane of the upper or sole-engaging surface of the pad P, this axis lying also in a vertical plane located substantially at the forward end of the pad engaging portion of the main or fixed casting 10. In order to accomplish this pivoting movement the casting 75 16 is provided at opposite sides of its lower wall

with a pair of downwardly projecting lugs 44 having slots 46 formed therein which engage the fixed shaft 32 and thus support the end of the casting 16 adjacent to the stationary casting 10. Another shaft 48, mounted in downwardly projecting ears or lugs formed on the lower side of the casting 16, is engaged inwardly of the lugs by ears 50 projecting upwardly from an adjustable supporting member 52 extending transversely of the pad box between the opposite side walls of the casting 16. The member 52 has a hole threaded internally to receive left-hand threads on the shank portion of a spiral gear 54 which, in turn, is provided with a right-hand threaded opening to receive the threaded portion of a stud 56 15 pivotally mounted on a short pin 58 extending transversely between ears 60 formed at the central portion of the base of the casting 10. The threads on the shank portion of the gear 54 are left-hand threads while those on the stud 56 are 20 right-hand so that rotation of the gear in a counterclockwise direction, as seen in plan view, will cause the gear to move upwardly on the right-hand threads of the stud as the supporting member 52 moves upwardly on the left-hand threads 25 of the shank of the gear 54. By this construction the movement of the supporting member 52 for each revolution of the gear 54 will be substantially increased. The spiral gear 54 is rotated by means of a worm gear 62 secured to a horizontal shaft 30 64 mounted in bearings in opposite sides of the casting 10, the shaft 64 projecting forwardly toward the operator, as viewed in Fig. 1, and being provided with a handle 66 by which it may be 35 rotated.

The shaft 48 projects beyond its bearings in the ears on the casting 16 and is flattened at its opposite ends, as shown in Fig. 1, to engage inclined slots 68 formed in the opposite side walls of the fixed casting 10, these slots being inclined 40 at an angle of approximately 75° to the horizontal. As the gear 54 is rotated by the worm 62, for example, in a counterclockwise direction, as seen in plan view, the shaft 48 is elevated swiftly in the inclined slots 68 thereby rotating the 45 casting 16 about the fixed shaft 32 and also moving it transversely of the shaft, the slots 46 permitting the casting 16 to move longitudinally of the pad relatively to the shaft 32 without losing contact therewith. The location of the shaft 32 50 and the direction of the inclined slots 68 are such that the casting 16 will be caused to rotate about a virtual axis or pivot which is located substantially in the plane of the sole-engaging surface of the pad and in a vertical plane separating 55 the fixed casting 10 from the movable casting 16, this plane coinciding substantially with the forward end of the shank portion of the pad. Since the casting 16 moves longitudinally of the casting 10 when it is adjusted into different angular 60 positions relatively thereto to cause the upper surface of the pad to conform more closely to the longitudinal contour of the shoe bottom, a thin plate 70 is secured to that surface of the casting 16 which engages the lower wall of the pad and is 65 arranged to overhang the inner edge of the casting thus covering the space separating the casting 16 from the casting 10 and preventing the lower wall of the pad from bulging out when pressure is applied to a shoe and sole mounted 70 thereon. The openings between the side walls of the two castings are likewise covered by a pair of thin plates 71 secured by screws to the upper portions of the opposite side walls of the stationary casting 10, as shown in Fig. 1. The sur- 75

face of the casting 16 which engages the lower wall of the pad is also provided with an opening 72 through which the pad may be filled with fluid, for example, water, any usual clamp and plug arrangement being utilized to seal the opening in the pad and thus prevent leakage, this being illustrated herein as a clamping bushing 74 having a threaded shank on which is mounted a clamping nut 75 and being provided also with an internal opening into which is threaded a plug 76.

The left-hand portion of the casting 16, as viewed in Figs. 1 and 2, extends upwardly relatively to the right-hand portion and has mounted on the upper surface of this raised portion a flat plate 78 secured in position by screws 80 and extending along each side wall of the casting 16 longitudinally of the pad box for the full length of the casting. The inner periphery 81 of the plate 78 (Fig. 3) conforms substantially to the shape of the forepart of a sole except that it is much larger than a sole and this peripheral portion projects beyond the adjacent edge of the casting 16 and fits into a recess 79 formed in the upper edge of the forepart of the pad P so that the plate 78 will hold the pad in position in the movable casting 16. The opposite lateral edges of the plate 78 project beyond the side walls of the casting 16 and serve as tongues upon which is slidably mounted a mask plate 82 somewhat greater in width than the casting 16 and having an inner periphery 84 which also conforms substantially to the outline of the toe end of a sole. The mask plate 82 is moved along the tongues provided by the plate 78 by a pair of small gears or pinions 86 and 87 secured respectively to the opposite ends of a horizontal shaft 88 rotatably mounted in suitable bearings in the casting 16. The pinions 86 and 87 are arranged to engage rack teeth 90 formed on the lower edges of flanged portions extending downwardly from the opposite sides of the mask plate 82. The shaft 88 is provided with a hand wheel 92 whereby the operator can rotate the pinions to move the mask plate into different positions longitudinally of the pad box.

In order to maintain the mask plate 82 in any position into which it may be adjusted longitudinally of the casting 16, there is secured to the forward side wall of this casting, as viewed in Fig. 1, a small plate 94 provided with a tooth which normally engages the teeth of the pinion 86, thus preventing the latter from being rotated. A compression spring 96 (Fig. 3) is provided at the opposite end of the shaft 88, one end of the spring being seated in a recess formed in the side wall of the casting 16 and the other end bearing against the inner surface of the pinion 87, the spring acting to maintain the shaft 88 at its innermost position relatively to the casting 16, this position being determined by the inner face of the forward pinion 86 bearing against the casting 16. When it is desired to move the mask plate into a different position longitudinally of the pad box, the operator pulls the shaft 88 forwardly against the action of the spring 96 by the handle 92, thereby disengaging the pinion 86 from the tooth on the fixed plate 94. The shaft is then rotated to move the mask plate into the desired position longitudinally of the pad box. Upon release of the handle the spring 96 moves the shaft 88 automatically back into its original position to cause the tooth on the plate 94 to engage the teeth of the pinion 86 and thus hold the mask plate in its adjusted

position. The longitudinal movement of the mask plate 82 rearwardly or away from the stationary casting 16 is limited by means of a downwardly projecting finger 98 (Fig. 1) secured by a screw to a forward portion of the mask plate 5 and arranged to engage a horizontal pin 100 carried by the plate 94 and projecting into the path of the finger 98. Movement of the mask plate in the opposite direction is limited by engagement of its forward edge with the upper portions of 10 the opposite side walls of the stationary casting 16.

The mask plate 82 carries a bracket 102 which is secured by screws 104 to the left-hand portion of its upper surface as viewed in Figs. 1 and 15 2. The width of the bracket 102 is somewhat less than the width of the mask plate and the bracket is provided at its inner portion with two outwardly diverging arms 106, 108 (Fig. 3) which, at their outer ends, carry vertical pins 110, 112, 20 which form, respectively, fixed pivots about which a pair of curved arms 114 and 116 rotate, each arm being provided with a sole-engaging finger or feeler as will presently be described. The arms 114 and 116 are arranged in crossed 25 relation to each other as shown in Fig. 3 and are operated yieldingly to engage the edge face of a sole at opposite sides substantially at the tip line thereby finding the sole and being positioned thereby. The arms are not mounted directly on 30 the pins 110, 112, since they are also arranged to rotate in a direction at right angles to their pivotal movement about these pins on a pair of horizontal pins 118 and 120 carried respectively in the outer ends of two inwardly extending 35 levers 122 and 124, fulcrumed directly on the vertical pins 110 and 112 and forming in effect inner arms for the curved arms 114, 116. The curved arms 114, 116 pivot freely about the horizontal pins 118, 120 in the levers 122, 124 and 40 are thus permitted to rest by their own weight on the sole-engaging surface of the pad as they are moved toward or away from the edge face of the sole by pivotal movement of the levers 122, 124 about the vertical pins 110, 112. The levers 45 122, 124 extend inwardly toward the center of the mask plate and at their inner ends are considerably wider than at their outer ends and are provided, respectively, with arcuate slots 126, 128, the arcs of which are struck from centers coinciding with the centers of the vertical pins 110, 112. The widened portions of the levers 122, 124 overlap each other so that the arcuate slots 126, 128 cross, as shown in Fig. 3.

Some distance inwardly of its opposite sides 55 the bracket 102 is provided with upwardly projecting walls 130, 132 (Figs. 1 and 3) the upper ends of which support a horizontal shaft 134 extending transversely or widthwise of the pad box, as shown in Fig. 1. Between the walls 130, 132 60 the upper surface of the bracket 102 is provided with a groove 136 extending longitudinally of the pad box and located substantially on its longitudinal median line. In the groove 136 is secured a tongue 138 which projects upwardly a 65 short distance above the groove, as shown in Fig. 2, and serves as a guideway for a slide plate 140 the lower surface of which is provided with a similar groove 142 fitting the tongue 138. At the left-hand end of the slide plate 140, as viewed 70 in Figs. 2 and 3, is mounted a transverse pin 144 which projects beyond each side of the plate 140 and serves as a pivot for a U-shaped arm 146 which extends forwardly under the curved arms 114, 116 and the inwardly extending levers 75

122, 124, and is provided with an abutment to be later described for engaging the toe end of a sole which is placed on the pad by the operator, the arm 146 being loosely pivoted on the pin 144 5 and resting by gravity on the surface of the pad. As shown in Fig. 2, the slide plate 140 underlies and supports the slotted portions of the levers 122, 124 and is provided with an elongated slot 150 a portion of which registers with the arcuate 10 slots 126, 128 in the overlapping portions of the levers. An upstanding pin 152, carried loosely in a hole in the bracket 102, extends upwardly through a hole in the tongue 138 and through the slot 150 and the arcuate slots 126, 128 in the 15 overlapping levers 122, 124, the pin 152 being provided at its upper end with an enlarged portion 154 which enters a recess in the forward end of a substantially horizontal arm 156 pivoted on a fixed shaft 158 secured by set screws in the 20 upwardly extending side walls 130, 132 formed on the bracket 102. A screw 160 extends into the recess in the arm 156 and engages the enlarged end of the pin 152 thus providing an adjustable stop for determining the distance which the pin 25 can enter the recess.

It will be noted in Fig. 2 that the recess in the 30 arm 156 is located a short distance to the right of the center of the shaft 158 so that as the arm is rotated in a clockwise direction about the shaft 158 the pin 152 will be forced downwardly in the bracket 102 with considerable force. Interposed between the enlarged end of the pin 152 and the slotted portion of the overlapping lever 124 is a 35 washer 162 which, when the arm 156 is rotated in a clockwise direction, is forced downwardly against the lever 124 to clamp this lever, the lever 122, and the slide plate 140, upon which the central arm 146 is mounted, against the bracket 102, thus locking the plate and the arms in the 40 positions they occupy at the time the member 156 is rotated. Opposite movement of the arm 156 will, of course, release the pressure on the pin 152 and unlock the overlapping levers and the slide plate thereby permitting the opposite 45 arms 114, 116 to be moved about their vertical pivots and the central arm 146 to be moved longitudinally of the mask plate by sliding movement of the plate 140 along the tongue 138.

The arms 114 and 116 are normally urged inwardly about the vertical pivots 110, 112 toward 50 a sole on the pad by means of a tension spring 164 connected at its opposite ends to upstanding pins 166, 168 mounted respectively in the levers 122, 124 some distance outwardly or to the left, as 55 viewed in Fig. 3 of the pivot pins 110, 112. The central arm 146 on the slide plate 140 is urged inwardly toward the sole by a torsion spring 170 (Figs. 1 and 3), one end of which is inserted in 60 a recess formed in an outwardly projecting portion 171 of the bracket 102 and the other end in a hole in the end of the plate 140.

In order to release the locking mechanism and move the arms away from the sole against the 65 action of the springs 164 and 170, there is provided mechanism carried by the mask plate and capable of being operated in any position into which the mask plate may be moved longitudinally of the casting 16. This mechanism is, in 70 turn, operated by further mechanism carried by a fixed bracket secured to the side of the casting 16 remote from the operator, as viewed in Fig. 1, and connected to mechanism forming a part of the sole-attaching machine referred to above, the latter mechanism being operated by a treadle on 75

such machine. This mechanism for operating the arms will now be described.

The opposite ends of the horizontal shaft 134 (Fig. 1) project laterally beyond the upstanding walls 130, 132 and have pivotally mounted thereon a U-shaped lever 172 the bar portion of which is located between the upstanding walls. The lever 172 is provided with a pair of downwardly extending arms 174, 176 located outside the walls 130, 132 and carrying respectively at their lower 10 ends horizontal pins 178, 180. The pins 178 and 180 project inwardly of the arms as viewed in Fig. 3 and are loosely engaged by the outer ends of a pair of substantially horizontal links 182, 184, these links having elongated slots 186, 188 15 formed at their opposite ends which respectively engage upstanding pins 190, 192 mounted on inner portions of the inwardly extending levers 122, 124 which carry the arms 114, 116.

The central or bar portion of the U-shaped 20 lever 172 has a cam surface 194 (Fig. 2) formed thereon which is located directly above the pivoted arm 156 and is arranged to engage a roll 196 mounted on a horizontal pin 198 extending transversely through a slot 200 formed in the central 25 portion of the arm 156. The other extremity of the arm 156, as viewed in Figs. 1 and 2, is provided with an adjustable screw 202 which extends through the arm 156 at right angles thereto and has a small projection formed on its lower 30 end for engaging and locating the upper end of a compression spring 204 the lower end of which is seated in a recess 206 formed in the outwardly projecting portion 171 of the bracket 102. The spring 204 tends normally to force the arm 156 35 in a clockwise direction about its pivot 158 to press the screw 160 against the head of the pin 152, thus forcing the pin downwardly in the bracket 102 and clamping the washer 162 against the overlapping portions of the levers 122, 124 40 and the slide plate 140, thereby locking the various arms against further movement. When the U-shaped lever 172 is rotated in a clockwise direction, as viewed in Fig. 2, the cam surface 194 45 engages the roll 196 and forces the arm 156 in a 50 counterclockwise direction about the pivot 158, thereby compressing the spring 204 and raising the forward end of the arm to release the pressure of the screw 160 on the pin 152 and thus unlock the levers 122, 124 and the slide plate 140. 55 Further clockwise movement of the lever 172 swings the depending arms 174, 176 toward the left thereby moving the links 182, 184 in the same direction to take up the lost motion provided by the elongated slots 186 and 188 in these 60 links so that the ends of the slots will engage the upstanding pins 190, 192 in the levers 122, 124. These levers are thereupon rotated about the pivots 110, 112 toward the left as viewed in Fig. 3 against the action of the spring 164, thereby 65 positively retracting the opposite arms 114 and 116 from the edge face of the sole.

The horizontal link 184 is provided about midway of its length with a laterally projecting pin 208 (Fig. 3) which is arranged to engage an 70 upstanding pin 210 carried by a forwardly extending arm 212 pivoted on a pin 214 mounted in the mask plate 82. Engagement of the pin 208 with the upstanding pin 210 rotates the arm 212 about the pivot 214 in a clockwise direction 75 as viewed in Fig. 3. The forward end of the arm 212 is reduced in size and is arranged to engage a small vertical pin 216 carried by a lug 218 projecting laterally from the rear side of the slide plate 140, the lug 218 being located above the 80

U-shaped arm 146 pivoted to this slide. By this arrangement as the arms 114, 116 are withdrawn by movement of the links 182, 184, the slide plate 140 and the central arm 146 are retracted along 5 the tongue 136. The lost motion provided by the slots in the horizontal links 182, 184 is approximately equal to the distance separating the pin 208 from the vertical pin 210 so that after this lost motion has been taken up and the arms 114, 10 116 begin to move away from the sole, the central finger 146 will also be moved rearwardly or away from the sole against the action of the torsion spring 170.

Rotation of the U shaped lever 172 about the 15 shaft 134 is accomplished by the following mechanism. On the further side of the lever 172, as viewed in Fig. 1, is provided a substantially horizontal arm 220 (Fig. 3) which extends to the left and is provided at its outer end with a roll 20 222 arranged to engage the upper surface of an elongated bar 224, the roll being held against the bar by a tension spring 226 the upper end of which is connected to the arm 220 by a pin 228 and the lower end to the movable casting 16. 25 The bar 224 extends longitudinally of the pad box for a distance somewhat greater than the length of the mask plate 82 and is supported by means of two pairs of toggles 230, 232 (Fig. 4), the lower links of which are pivotally mounted on 30 fixed pins 234, 236 carried in lugs 238, 240 projecting laterally from the farther side wall of the casting 16. The bar 224 is connected to the upper links of the toggles 230, 232 by pins 231, 233 which extend beyond the inner sides of the 35 links for some distance and carry rolls 260 and 262, the purpose of which will presently be explained. The lugs 238 and 240 on the casting 16 are elongated, as shown in Fig. 4, and have mounted on the portions thereof opposite the 40 pins 234, 236 a bracket 242 which is secured to the lugs by means of screws 244 and 246, and a third screw 248 mounted in a downwardly extending arm 249 of the lug 238 and arranged to fasten a lower arm 250 of the bracket 242 to the 45 lug 238, thereby strengthening the mounting of the bracket on the casting. The upper side of the bracket 242 is provided at its opposite ends with two upwardly projecting portions 252, 254 provided respectively with elongated slots 256, 258 which extend substantially at right angles to 50 the upper surface of the mask plate 82. The rolls 260, 262 previously referred to as being mounted on the toggle pins 231, 233 are arranged to enter the slots 256, 258 and thus control the 55 direction of the movement of the upper ends of the toggle links and also of the elongated bar 224. The links of each pair of toggles 230, 232 are connected together by pins 264, 266 and another link 268 extends between these pins substantially 60 parallel to the bar 224 to connect the centers of each pair of toggles so that the toggles will be operated simultaneously. The inner or right-hand end of the connecting link 268 as viewed in Fig. 4 extends beyond the pin 266 and is connected to a short intermediate link 270 which, in turn, is pivotally connected to the upper end of an upwardly projecting arm of a bell crank lever 272, the latter forming a part of the operating mechanism of the cement sole-attaching 65 machine disclosed in the Ballard application Serial No. 636,202 mentioned above.

Before proceeding to describe in detail the mechanism which actuates the toggles 230, 232 it should be explained that the sole-engaging members or arms 114 and 116 are provided respec-

tively on their outer ends with sole-engaging fingers or feelers 274, 276, sometimes referred to hereinafter as sole finders, and that the central U shaped arm 146 is likewise provided with a sole-engaging feeler or finder 278 as shown in 5 Figs. 2 and 3. Each of these fingers or feelers carries a shoe gage mounted in superposed relation thereto, the shoe gages being indicated, respectively, in Fig. 3 by the reference numerals 280, 282 and 284. The shoe gages are slidably 10 mounted on the sole feelers and are arranged for adjustment relatively thereto through the rotation of manually operated frusto-conical members mounted on the feelers and provided with pins located eccentrically with respect to centers 15 of the said members and entering transverse slots in the shank portions of the shoe gages whereby the latter may be moved in guideways formed in the upper surfaces of the sole-engaging feelers, this mechanism being fully shown 20 and described in the above-mentioned Ballard application, Serial No. 636,202. This construction is to permit adjustment of the shoe gages relatively to the feelers or finders to accommodate shoes the soles of which may extend beyond 25 the shoe upper different amounts, as is common in some styles of shoes.

The machine in the application referred to is also provided with a forwardly and rearwardly swinging frame member 290 (Fig. 1) which 30 carries suitable abutments 292 and 294 for engaging the shoe and last and forcing the shoe and sole downwardly against the upper face of the pad to apply the sole-attaching pressure, a handle 296 being provided whereby the swinging 35 frame may be moved forwardly by the operator into operative position over the shoe. Since this mechanism forms no part of the present invention it is not described in detail herein and reference may be had to the Ballard application mentioned above for a full disclosure thereof.

Returning now to the mechanism for operating the two pairs of toggles 230, 232, the upper arm of the bell crank lever 272 (Figs. 4 and 5) is moved to the left to straighten the toggles, elevate the bar 224, and, through the arm 220, to rotate the U-shaped lever 172, thereby moving the horizontal links 182, 184 away from the sole and by means of the connections already described, positively withdrawing the opposite sole-engaging feelers 274, 276 and the central feeler 278 with their corresponding shoe gages away from the sole and shoe. The bell crank lever 272 is fulcrumed at 298 to a suitable part of the rotating turret of the machine as disclosed in 55 the Ballard application previously referred to. A tension spring 300 anchored at 302 to the up-standing arm of the bell crank lever 272 and at 304 to the frame of the machine urges the bell crank lever in a clockwise direction as viewed in 60 Fig. 5 until an adjustable stop 306 carried by the lever 272 engages a stationary abutment 308, the spring 300 tending normally to break the toggles and to permit the various sole-engaging members to be urged inwardly toward the edge face 65 of the sole by the springs 164 and 170.

A rod 310 extends upwardly from a treadle 312 of the machine forwardly of the fulcrum of the treadle and is pivoted at 314 to a lever 316 which is fulcrumed at 318 to a stationary cam track 320 70 adjacent to the operating station of the machine and in close proximity to the path of movement of an approximately horizontal arm 322 of the bell crank lever 272 as the pad box moves into and away from the operating station. A roll 324 car- 75

ried by the arm 322 rides along the cam track 320 as the pad box approaches the operating station and rocks the lever 272 in a counterclockwise direction, as viewed in Figs. 4 and 5, thereby moving the horizontal link 268, which connects the toggles 230, 232, toward the left, thus straightening the toggles. This action causes the roll 222 on the arm 220 to be elevated by the bar 224 to retract the feelers and their shoe gages from the sole and shoe.

A movable cam track section 326 carried by the lever 316 forms a continuation of the cam track 320 and is so positioned that the turret of the machine comes to rest with the roll 324 on the lower arm of the bell crank lever 272 upon the cam track section 326. With the parts in this position the bell crank lever 272 has been rocked in a counterclockwise direction from the position shown in Fig. 5 so that the toggles have been straightened to withdraw the feelers and gages from the sole and shoe. After the shoe previously operated upon has been removed and another sole has been placed upon the pad with its forepart in position to be engaged by the various feelers the operator depresses the treadle 312 thereby moving the cam track section 326 downwardly. This permits the bell crank lever 272 to move in a clockwise direction into the position shown in Fig. 5 under the action of the tension spring 300, thereby moving the connecting link 268 to the right, as viewed in Fig. 4, to break the toggles 230, 232, lower the elongated bar 224, and permit the sole-engaging feelers to move inwardly yieldingly to find the edge face of the sole under the action of their springs 164 and 170.

In order that it will not be necessary for the operator to hold his foot on the treadle 312 a latch lever 328 is fulcrumed at 330 to the cam track 320. The latch lever 328 is provided with a shoulder 332 adapted to engage a hardened steel plate 334 secured to the lever 316 and the latch lever is urged in a counterclockwise direction as viewed in Fig. 5 by a tension spring 336. When the treadle 312 is depressed the latch lever 328 is moved by the spring 336 until its shoulder 332 snaps past the end of the hardened plate 334, thereby latching the lever 316 in the lowered position shown in Fig. 5. The operator may now remove his foot from the treadle 312.

After the forepart of a sole has been found and engaged by the feelers 274, 276, and 278 and the forepart of a shoe has been inserted between the shoe gages which are now locked in position so that they will locate the shoe relatively to the sole, and after the last and shoe-engaging abutments 292 and 294 of the machine have been moved downwardly into engagement with the last and shoe to apply the sole-attaching pressure to the shoe and sole, the turret-rotating mechanism of the machine is operated in the manner disclosed in the Ballard application Ser. No. 636,202 and the bell crank lever 272 is moved bodily to the right as viewed in Fig. 5. In order to release the latch 332 and permit the lever 316 to rise, a cam roll 338 is carried by the bell crank lever 272, the axis of the roll coinciding with the axis about which the bell crank lever 272 is fulcrumed. As the roll 338 moves to the right it first engages the upper side of the lever 316 and then engages an upwardly extending cam surface 340 formed on a finger extending to the right from the latch lever 328, thereby rocking this lever in a clockwise direction against the tension of the spring 336 and, since the roll 338 has by this time

passed out of engagement with the lever 316, permitting the latter to rise.

As illustrated, the lower end of the rod 310 is surrounded by a compression spring 342 bearing at its upper end against an abutment 344 adjustably mounted on the rod 310 and, at its lower end, against a suitable surface on the treadle 312. The lower end of the rod 310 passes loosely through a hole in a suitable part of the treadle 312 and is provided with an enlarged collar so that depression of the treadle positively depresses the rod 310. The treadle is held normally in an inoperative position by means of a treadle spring 346 secured at its lower end to a suitable portion of the treadle and at its upper end to a hook 348 threaded into a lug on a stationary portion of the frame of the machine. The latching mechanism is so constructed, however, as to permit the rod 310 to be forced downwardly by the roll 324 against the compression of the spring 342 which is lighter than the treadle spring 346. It will be noted that the toggles 230, 232 may be straightened or broken by the mechanism just described to move the bar 224 upwardly or downwardly irrespectively of the position longitudinally of the pad box into which the mask plate 82 and the mechanism carried thereby are moved. Moreover, the length and position of the bar 224 are such that the U shaped lever 172 will be rotated by the bar to operate the sole and shoe-engaging mechanism in any position into which the mask plate 82 may be moved. Consequently, the mask plate may be adjusted toward the right, as viewed in Fig. 2, to accommodate a small shoe such, for example, as an infant's or a child's shoe, or it may be adjusted toward the left to accommodate larger shoes, such as youths' or misses' shoes, without affecting the operation of the sole and shoe-positioning mechanism in the least.

As illustrated in Figs. 1 and 2, the pad box is provided with means which has an effect similar to that which would be produced by adding fluid to the pad when a small shoe is to be operated upon and by removing fluid from the pad when a large shoe is to be operated upon, thereby changing the contour of the upper or sole-engaging surface of the pad to accommodate different sizes of shoes. This means comprises a movable plate 350 pivoted on the shaft 32 and having an extension 352 pivotally mounted on its rear or right-hand end, the extension being arranged to enter a recess or groove 354 in the upper end of the upstanding wall 37 so that the members 350 and 352 form, in effect, a hinged plate or door for supporting the lower wall of the pad substantially under the shank portion of the shoe. The hinged plate 350 is moved about its pivot 32 by a polygonal cam 356 mounted on a transverse shaft 358 which is provided with a hand wheel 360 (Fig. 1) by which the cam may be rotated to move the plate and the lower wall of the pad toward or away from the sole-engaging wall of the pad, thereby changing the contour of the sole-engaging surface of the pad to adapt it for the size of shoe which is to be operated upon. The above mechanism forms no part of the present invention and accordingly is not described in further detail herein. It is, however, fully described and claimed in an application for Letters Patent of the United States Ser. No. 722,537, filed April 26, 1934, in the name of Frank Kennison.

Having described our invention, what we claim as new and desire to secure by Letters Patent of the United States is:

1. A machine for applying pressure to shoe

- bottoms having, in combination, a pad box, a pad in the box for receiving a sole, means carried by the pad box and movable longitudinally thereof for finding the edge faces of a sole resting on the pad, and means for actuating said finding means 5 yieldingly in any position longitudinally of the pad box.
2. A machine for applying pressure to shoe bottoms having, in combination, a pad box, a pad 10 in the box for receiving a sole, sole-engaging means carried by the pad box and adjustable longitudinally thereof for finding the opposite edge faces of the forepart of a sole located on the pad by an operator, and means for actuating the 15 sole-engaging means to find the sole without moving it on the pad irrespective of the position of said last-named means longitudinally of the pad.
3. A machine for applying pressure to shoe 20 bottoms having, in combination, a pad box, a pad in the box for receiving a sole, a pair of sole-engaging fingers movable lengthwise of the pad to engage soles of different lengths positioned thereon, and means fixed longitudinally of the 25 pad box for actuating said fingers in any position of the fingers lengthwise of the pad.
4. A pad box for applying pressure to shoe bottoms having, in combination, a pad for receiving a sole, a mask plate overlying said pad and 30 movable longitudinally thereof, and relatively movable sole-engaging fingers movable longitudinally of the pad with said mask plate.
5. A pad box for applying pressure to shoe bottoms having, in combination, a pad for receiving a sole, a mask plate overlying only the 35 forepart of said pad and arranged for movement longitudinally thereof, and a plurality of sole-engaging feelers mounted on the mask plate and arranged to find a sole positioned on the pad.
6. A pad box for applying pressure to shoe 40 bottoms having, in combination, a pad for receiving a sole, a mask plate overlying said pad and movable relatively thereto, relatively movable sole-engaging fingers carried by and movable with the 45 mask plate and arranged to find the opposite sides of a sole mounted on the pad, and means for moving said mask plate.
7. A pad box for applying pressure to shoe 50 bottoms having, in combination, a pad for receiving a sole, a mask plate overlying said pad and movable longitudinally of the pad box, a pair of sole-engaging fingers carried by the mask plate, manually operated means for moving the mask plate longitudinally of the pad box, and 55 means for limiting the longitudinal movement of the mask plate.
8. A pad box for applying pressure to shoe 60 bottoms having, in combination, a pad for receiving a sole, a mask plate overlying said pad and arranged for movement longitudinally thereof, means for moving said mask plate, and means operating automatically for holding the mask plate in different positions lengthwise of the pad.
9. A pad box for applying pressure to shoe 65 bottoms having, in combination, a pad for receiving a sole, a mask plate overlying said pad and adjustable longitudinally thereof, sole-engaging feelers mounted on the mask plate and movable therewith, manually operated means for adjusting the mask plate longitudinally, and means mounted on the pad box for maintaining the mask plate in adjusted position.
10. A machine for applying pressure to shoe 70 bottoms having, in combination, a pad box, a 75 pad in the box for receiving a sole, a mask plate overlying the forepart of said pad and movable longitudinally thereof, sole-engaging fingers mounted on the mask plate and movable therewith to engage soles of different lengths, and means for actuating said fingers in any position into which the mask plate may be moved.
11. A machine for applying pressure to shoe 10 bottoms having, in combination, a pad box, a pad in the box for receiving a sole, a mask plate 15 overlying said pad and movable longitudinally of the pad box, a pair of sole-engaging feelers carried by the mask plate and movable therewith, said feelers being arranged to find a sole placed on the pad by an operator, and means for actuating said feelers irrespective of their position longitudinally of the pad.
12. A pad box for applying pressure to shoe 20 bottoms having, in combination, a pad for receiving a sole, a mask plate overlying the forepart 25 of the pad and adjustable longitudinally thereof, sole-engaging feelers carried by the mask plate and arranged yieldingly to engage the forepart of a sole positioned on the pad by an operator, and means mounted on the pad box for adjusting the mask plate longitudinally to locate the feelers properly for engaging soles of different lengths.
13. A machine for applying pressure to shoe 30 bottoms having, in combination, a pad box, a pad in the box for receiving a sole, a mask plate 35 overlying the pad and arranged for movement longitudinally thereof, sole-engaging feelers carried by and movable with the mask plate for finding the edge faces of a sole mounted on the pad, shoe gages carried by the feelers, and means mounted on the pad box for actuating said feelers and gages in any position into which they may be moved longitudinally of the pad.
14. A machine for applying pressure to shoe 40 bottoms having, in combination, a pad box, a pad in the box for receiving a sole, a mask plate overlying the forepart of the pad and arranged for movement longitudinally thereof, a pair of 45 sole-engaging fingers carried by and movable with the mask plate for engaging the forepart of a sole resting on the pad, shoe gages carried by said fingers, and manually-controlled means independent of the mask plate for operating said fingers.
15. A pad box for applying pressure to shoe 50 bottoms having, in combination, a pad for receiving a sole, a mask plate overlying the forepart of the pad and adjustable longitudinally thereof, sole-engaging feelers carried by the mask 55 plate and movable laterally of the pad to find the forepart of a sole placed thereon, manually operated means for adjusting the mask plate longitudinally of the pad to position the feelers properly for soles of different sizes, and means mounted on the pad box for limiting the longitudinal movement of the mask plate.
16. A pad box for applying pressure to shoe 60 bottoms having, in combination, a pad for receiving a sole, a mask plate overlying the pad and movable relatively thereto, a pair of sole-engaging fingers mounted on the mask plate and movable therewith, said fingers being arranged to engage the opposite edge faces of a sole on the pad, and a third finger for engaging the 65 end of the sole.
17. A pad box for applying pressure to shoe 70 bottoms having, in combination, a pad for receiving a sole, a mask plate overlying one end of the pad and having its inner edge shaped to con- 75

form substantially to the periphery of a sole, said mask plate being adjustable lengthwise of the pad, a pair of sole-engaging fingers carried by and adjustable with the mask plate for engaging the opposite edge faces of a sole mounted on the pad, and a third finger carried by the mask plate for engaging the end of the sole.

18. A machine for applying pressure to shoe bottoms having, in combination, a pad box, a pad in the box for receiving a sole, a mask plate overlying the forward end of the pad and arranged for adjustment longitudinally thereof to accommodate soles of different lengths, a pair of sole-engaging feelers mounted on the mask plate and adjustable therewith for engaging the forepart of a sole on the pad substantially at the tip line, a central feeler carried by the mask plate for engaging the toe end of the sole, means on the pad box for adjusting the mask plate longitudinally of the sole, and means independent of the mask plate for actuating all of said feelers in any position into which the mask plate may be adjusted.

19. A machine for applying pressure to shoe bottoms having, in combination, a pad box, a pad in the box for receiving a sole, a mask plate overlying the forepart of the pad and having its inner periphery shaped to conform substantially to the toe portion of a sole, said mask plate being adjustable longitudinally of the pad box, a pair of sole-engaging fingers carried by and adjustable with the mask plate for engaging the opposite edge faces of a sole in the vicinity of the tip line irrespective of the length of the sole, a finger on the mask plate for engaging the toe end of the sole, and manually operated means for actuating all of said fingers in all positions into which the mask plate may be adjusted.

20. A machine for applying pressure to shoe bottoms having, in combination, a pad box, a pad in the box for receiving a sole, a mask plate mounted on the forward end of the pad box for preventing excessive bulging of the sole-engaging surface of the pad when pressure is applied to the sole, said mask plate being movable in a predetermined plane longitudinally of the pad so that it may be positioned properly for soles of different lengths, feelers movable with the mask plate for finding the forepart of a sole substantially at the tip line, said feelers being pivotally arranged to rest by gravity on the sole-engaging surface of the pad, and means carried by the pad box for actuating said feelers irrespective of their positions longitudinally of the pad.

21. A machine for applying pressure to shoe bottoms having, in combination, a pad box, a pad in the box for receiving a sole, a mask plate movable longitudinally of the pad, a pair of fingers pivoted on the mask plate for engaging the forepart of a sole placed on the pad, a third finger slidably mounted on the mask plate for engaging the toe end of the sole, and manually controlled means mounted on the pad box independently of the mask plate for moving all of said fingers yieldingly against the sole, said means being constructed and arranged to actuate the fingers in whatever positions they may occupy longitudinally of the pad.

22. A machine for applying pressure to shoe bottoms having, in combination, a pad box, a pad in the box for receiving a sole, a mask plate movable longitudinally of the pad, a pair of feelers pivotally mounted on the mask plate for finding the forepart of a sole positioned on the pad by an operator, a central feeler slidably mounted on

the mask plate for finding the toe end of the sole, means mounted on the pad box for moving all of said feelers yieldingly against the edge face of the sole, and means for retracting the feelers in whatever positions they may occupy longitudinally of the pad.

23. In a machine for cement-attaching soles to shoes, the combination of a pad for applying pressure to shoe bottoms, a mask plate covering the forepart of said pad to prevent excessive bulging thereof when pressure is applied to the shoe bottom, said mask plate being movable relatively to the pad to adapt it for operating upon soles of different lengths, sole-engaging members pivoted on the mask plate and movable therewith, said members comprising a pair of fingers for engaging opposite sides of a sole on the pad and a third finger for engaging the toe end of the sole, manually-controlled means for moving said fingers yieldingly against the edge face of the sole, and means for automatically retracting the fingers after they have engaged the sole, said retracting means being constructed and arranged to operate in any position into which the mask plate may be moved longitudinally of the pad.

24. In a machine for cement-attaching soles to shoes, the combination of a pad box for applying pressure to shoe bottoms, a fluid-filled pad in the box for receiving a sole, a mask plate overlying the forward portion of said pad to prevent excessive bulging of its sole-engaging surface when pressure is applied to the shoe bottom, said mask plate being movable longitudinally of the pad to adapt it for operating upon soles of different lengths, sole and shoe-engaging members pivoted on the mask plate and movable therewith, said members comprising fingers for engaging the sides and ends of the foreparts of a sole and shoe, springs for moving the fingers yieldingly against the edge face of a sole positioned on the pad, and manually-controlled means for allowing the springs to operate said fingers and for positively withdrawing the fingers after pressure has been applied to the sole and shoe, thereby retensioning the springs, said means being constructed and arranged to operate in any position into which the mask plate may be moved longitudinally of the pad box.

25. A machine for applying pressure to shoe bottoms having, in combination, a pad box, a pad in the box for receiving a sole, sole-engaging feelers carried by the pad box and movable longitudinally thereof for finding the edge face of a sole resting on the pad, means for actuating said feelers irrespective of their positions longitudinally of the pad box, and means for locking the feelers against opening movement after they have found the edge face of the sole.

26. A machine for applying pressure to shoe bottoms having, in combination, a pad box, a pad in the box for receiving a sole, a pair of fingers carried by the pad box and movable about axes located at opposite sides of the pad and each finger arranged to engage the edge face of a sole positioned on the pad at the side of the pad opposite that at which its axis is located, means for adjusting said fingers longitudinally of the pad box to position them properly for the sole being operated upon, and means for moving the fingers about their axes into engagement with the edge faces of the sole in any position into which the fingers may be adjusted longitudinally of the pad.

27. A machine for applying pressure to shoe bottoms having, in combination, a pad box, a

pad in the box for receiving a sole, a mask plate overlying said pad and movable longitudinally thereof, a pair of sole-engaging fingers pivoted about axes mounted on the mask plate at opposite sides of the longitudinal center line of the pad, said fingers being arranged in crossed relation to each other, a third finger slidably mounted on the mask plate between the crossed fingers for engaging the end of the sole, means for actuating said fingers in any position of the mask plate longitudinally of the pad, and means for locking the fingers after they have engaged the sole.

28. A machine for applying pressure to shoe bottoms having, in combination, a pad box, a pad in the box for receiving a sole, a mask plate overlying the forepart of the pad and adjustable longitudinally thereof to accommodate soles of different lengths, a pair of sole-engaging feelers pivoted about centers mounted on the mask plate at opposite sides thereof, said feelers being located in crossed relation to each other and arranged to find the forepart of a sole on the pad substantially at the tip line, a third feeler slidably mounted on the mask plate for finding the toe end of the sole, shoe gages carried by said feelers and arranged to position the forepart of a shoe relatively to the sole, means for moving said feelers yieldingly into engagement with the sole, said means being constructed and arranged to operate the feelers in any position into which the mask plate may be adjusted longitudinally of the pad, and means carried by the mask plate for locking the feelers after they have found the sole, thereby locating the shoe gages properly for positioning the shoe relatively to the sole.

29. A machine for applying pressure to shoe bottoms having, in combination, a pad box, a pad carried by the box for receiving a sole and shoe, a mask plate overlying the forward end of the pad and movable longitudinally of the pad box, manually-operated means on the pad box for moving said mask plate, sole finders pivotally mounted on the mask plate and movable therewith, said finders carrying shoe gages for positioning a shoe relatively to a sole, springs for moving said finders yieldingly to find a sole placed on the pad thereby to position the shoe gages relatively to the sole, manually-controlled means for releasing the tension on the springs and thereby permitting them to operate the finders, and means for positively withdrawing said finders from engagement with the sole and for holding them in withdrawn positions against the tension of the springs, said releasing means and said withdrawing means being constructed and arranged to operate in any position into which the mask plate may be moved longitudinally of the pad box.

30. A machine for applying pressure to shoe bottoms having, in combination, a pad box, a pad in the box for receiving a sole and shoe, a mask plate overlying the forward end of the pad and adjustable longitudinally thereof, a pair of sole and shoe-engaging fingers pivoted about centers mounted on the mask plate at opposite sides of the longitudinal center line of the pad, manually-operated means for adjusting the mask plate longitudinally of the pad thereby positioning the fingers for shoes of different lengths, sep-

arate means for holding the mask plate in adjusted position, springs for moving the fingers yieldingly about their pivots to engage a sole resting on the pad thereby positioning the shoe-engaging fingers relatively to the sole, means movable with the mask plate for locking the fingers after they have engaged the sole, and means for unlocking the fingers and positively returning them to initial position, said last-named means being constructed and arranged to operate irrespective of the position into which the mask plate is adjusted longitudinally of the pad.

31. A pad box for applying pressure to shoe bottoms comprising a pad for receiving a sole, a support for said pad comprising a fixed member underlying the shank and heel engaging portions of the pad and a movable member connected to said fixed member and underlying the forepart of the pad, said movable member being arranged to pivot relatively to the fixed member about a transverse axis located in a plane coinciding substantially with the sole-receiving surface of the pad, and expansible means connecting the movable member to the fixed member for causing said movable member to pivot about said axis.

32. A pad box for applying pressure to shoe bottoms having, in combination, a pad for receiving a sole, a supporting structure for said pad comprising a fixed member underlying the shank and heel portions of the pad, and a movable member underlying the forepart of the pad, said movable member being connected to the fixed member and being arranged to pivot about said member on a virtual axis located substantially at the forward end of the pad engaging portion of the fixed member and in a plane coinciding substantially with its sole-receiving surface, and manually-operated means remote from said virtual axis for pivoting the movable member about said axis, said means including a fixed support, a movable support, and means for causing the movable support to travel in a predetermined path while permitting the movable member of the supporting structure to remain in engagement with said fixed support.

33. A pad box for applying pressure to shoe bottoms having, in combination, a pad for receiving a sole, a supporting structure for said pad comprising a fixed member underlying the shank and heel portions of the pad and a movable member underlying the forepart of the pad, said movable member being constructed and arranged to pivot relatively to the fixed member about a predetermined axis coinciding substantially with the forward end of the pad engaging portion of the fixed member and in the plane of the sole-engaging surface of the pad, a stationary shaft on the fixed member for supporting that end of the movable member adjacent to said fixed member, mechanism including a worm and gear for elevating the forward portion of the movable member, and means on the fixed member for causing said elevating mechanism to move the movable member in a predetermined path so that the combined action of the elevating mechanism and the stationary shaft will cause the movable member to pivot about said predetermined axis.

FRANK KENNISON.
JAMES R. O'BRIEN. 70
